UNITED STATES PATENT OFFICE.

JAMES C. THERIOT, OF TAFT, CALIFORNIA.

SAFETY ATTACHMENT FOR WELL-DRILLING TOOLS.

1,212,848.

Specification of Letters Patent Patented Jan. 16, 1917.

Application filed June 30, 1915. Serial No. 37,285.

To all whom it may concern:

Be it known that I, JAMES C. THERIOT, a citizen of the United States, residing at Taft, in the county of Kern and State of California, have invented certain new and useful Improvements in Safety Attachments for Well-Drilling Tools; and I do hereby declare the following to be a full, clear, and exact description of the invention, such as will enable others skilled in the art to which it appertains to make and use the same.

This invention relates to new and useful improvements in safety attachments for well drilling tools and the principal object of the invention is to provide a device which will automatically signal the operator when the drill bit becomes broken or otherwise disconnected from the drill shaft.

Another object of the invention is to provide a device which will cause the pump to buck or to completely stop in event that the drill bit becomes twisted or broken from the drill stem or shaft.

A further object of the invention is to provide an automatic means for stopping the circulation through the pump and for causing the water to back up into the pump so as to warn the operator of the danger of losing the drill bit or the part carried thereby.

30 A still further object of the invention is to provide a valve which will automatically close upon the descent of the drill shaft, should the drill bit become twisted or broken off.

35 A further object of the invention is to provide a device, which when the drill shaft is broken will let the operator know that the shaft is separated from the drill bit and is held by the safety so that the lower part

40 can be pulled up for repairs.

A still further object of the invention is to provide a device which will release the automatic valve as soon as the pipe is lifted, thereby continuing the circulation of water.

45 With these and other objects in view, the invention consists in the novel combination and arrangement of parts which will be fully set forth in the following specification and accompanying drawings, in which:—

50 Figure 1 is a view illustrating this improved device as it would appear when in use and under normal conditions. Fig. 2 is

an enlarged longitudinal sectional view through a portion of the device illustrating in detail the several parts. Fig. 3 is a view 55 partly in section of the drill head, and the drill bit. Fig. 4 is an enlarged fragmentary view of the drill shaft showing the method of joining two of the sections, and Fig. 5 is a view illustrating the water tight connection 60 between the drill shaft and the conductor pipe.

Referring now to the drawings by characters of reference, the numeral 1 designates the drill shaft of the device comprising a 65 plurality of tubes of the ordinary type used in connection with well drilling, which are connected at their ends by the couplers best illustrated in Fig. 4. These couplers are designated by the numeral 2 and comprise 70 the cylindrical bodies 3 provided with external screw threads 4 and formed at one end of each of the bodies is a suitable enlargement 5 provided with internal screw threads 6. The enlargement 5 is arranged 75 to receive the externally screw threaded end of one of the tubes, while the threaded body 3 extends into an internally screw threaded socket carried by one of the tubes.

Secured to the lowermost end of the lowermost section of drill shaft or tube is a 80 drill head designated generally by the numeral 7 comprising the body 8 having internal screw threads formed therein and this body is provided with the hollow extension 9 having the tapered inner bore 10 formed with screw threads by means of which the drill designated generally by the numeral 11 is held in place. This drill comprises the threaded stem 12, which tapers 85 toward its outer end and the blades 13, the lower ends of which are flared as at 14. The tapered stem 12 is arranged to be threaded into the tapered bore 10 and the stem is preferably hollow to allow for the circulation of 90 the water when the drill is in operation. A suitable extension 15 is formed on the drill head body 8 at the end opposite the extension 9 and this extension 15 is provided with internal screw threads 16 which engage the 95 threads at the lowermost end of the lower shaft section hereinbefore referred to.

Threaded into the body 8 is a hollow pipe 17 provided with the longitudinal recess or

opening 18 and having formed at one end the reduced extension 19 which is formed with a longitudinal opening, the walls of which coincide with the wall of the opening 18. The point where the reduced extension 19 joins the body 17 forms a shoulder 20, against which the packing which will be more fully hereinafter described engages. A suitable screw thread 21 is formed at the free end of the extension 19 and is arranged to receive the nut 22 and lock nut 23, which form abutments for the upper end of the rotatable sleeve 24, which is fitted on the extension 19. This sleeve 24 is provided with an enlarged bore 25, in which the packing 26 seats. Suitable external screw threads 27 are formed at the upper end of the sleeve and are arranged to form a connection for the conductor pipe, which will be more fully 20 hereinafter described.

The conductor pipe hereinbefore referred to is best illustrated in Figs. 2 and 5 and comprises the hollow tube or pipe sections 28, to the lowermost end of which is connected the sleeve 24, by means of the threads 27. The upper end of the uppermost of these pipe sections 28 has connected thereto a suitable sleeve 29, which is held in place by means of screw threads and the set screw 30 and threaded on the upper end of the sleeve 29 is the bushing 31 provided with an internally screw threaded bore 32. Extending through the bushing and supported by the threads 32 therein is the externally 35 screw threaded adjusting pipe 33, the lower end of which extends into the pipe 28, while the upper end is formed with the valve seat 34 and extends into the valve cage which will be more fully hereinafter described.

40 Supported on suitable transversely extending rivets 35, which project at right angles to each other within one of the sections of shaft 1 is the cage designated by the numeral 36 comprising the pipe 37 having formed therein a plurality of longitudinal slots 38, which are arranged at ninety degrees from each other and threaded into the lower end of the pipe 37 is a bushing 39 having the shoulder 40 formed at its lower 45 end, which abuts the lower end of the pipe. The upper end of this bushing is provided with the valve seat 41 and formed in the pipe 37 and bushing 39 near the upper end of said bushing are a plurality of openings 42, which allow the circulating water to 50 flow down the interior of the drill shaft 1 and into the adjusting pipe 33, from whence it passes into the conductor pipe 28 and thence through the tube 17 into the bit 11.

55 In order to prevent the water from flowing into the shaft 1 below a predetermined height, there is provided the packing member best illustrated in Fig. 5, comprising the sleeve 43 having the body 44, the opposite ends of which are formed with the internal

bores 45 and 46 respectively. The bore 45 is relatively short and provided with internal screw threads 47 into which the shaft 1 is threaded. The bore 46 is relatively long and is provided with internal screw 70 threads 48 in which the section above the first mentioned of shaft 1 is threaded. Intermediate the shoulder formed by the lower end of the upper section of the shaft 1 and the shoulder formed by the lower end of the bore 46 is provided a suitable watertight packing 49, which will prevent the water from entering the shaft 1 immediately below the sleeve 43. It will thus be seen that the shaft below the sleeve 43 will be kept clear 80 of any water.

In operation it will be seen that should the drill head or any part of the drill shaft twist off or break so that the bit becomes disconnected therefrom, the shaft will lower 85 slightly, thereby lowering the cage 36 and permitting the opening 42 to be closed by seating of the ball 41' against the valve seat 34. It will thus be seen that the circulation of water down through the shaft 1, 90 openings 42 and adjusting pipes 33 into the connector pipe 38 will be stopped so that the water above the ball 41' will back up into the pumps, thereby causing the same to buck or stopping the action thereof entirely, 95 thus giving the signal to the operator, so that the proper steps may be taken to continue the drilling operation. Under normal working conditions, when the drill is acting properly, it will be noted that the cage will 100 be supported in such a position that the ball 41' will be suspended above the valve seat 34 and the openings 42 will be cleared so that the circulation through the drill and through the well will be maintained without interference. 105

While in the foregoing there has been shown and described the preferred embodiment of this invention, it is to be understood that such changes may be made in the combination and arrangement of parts as will fall within the spirit and scope of the appended claims. 110

What is claimed is:—

1. A device of the character described including a hollow drill shaft, a drill bit mounted at the lower end of the shaft, a valve cage intermediate the ends of the shaft, a valve within the cage, a conductor pipe within the shaft below the valve, the valve controlling the flow of water through the conductor pipe and means to allow the valve to automatically close upon accidental disconnection of the drill bit from the shaft. 115

2. A device of the character described including a hollow shaft, a drill head at the lower end of the shaft, a drill bit carried by the head, a conductor pipe swivelly connected to the drill head and disposed within the drill shaft, a valve cage intermediate the 120

125

ends of the shaft, a pipe connecting the lower end of the valve cage with the conductor pipe, a valve within the cage, a valve seat at the upper end of the pipe connecting the cage with the conductor pipe and means to hold the valve out of engagement with the valve seat under normal working conditions and allowing the valve to operate upon acci-

dental disconnection of the drill bit from the shaft.

In testimony whereof I affix my signature in presence of two witnesses.

JAMES C. THERIOT.
